LITHOGRAPHIC MACHINE

Roy Aberle, Long Branch, N. J.

Application February 8, 1938, Serial No. 189,445

4 Claims. (Cl. 101—142)

This invention relates generally to printing machines and more particularly to such machines wherein printing matter is transferred from a lithographic printing plate to an offset rubber blanket or impression cylinder and therefrom to a blank sheet of paper.

Among the objects of this invention is the provision of structure for the rapid and positive transfer of individual sheets of paper successively through the lithographic printing process.

An object herein is the provision of structure for obtaining accurate registration of each sheet with relation to the printing impression on the offset cylinder thereof as said sheet is carried through the printing machine.

Another object of the present invention is the provision of means for positively gripping each of the individual sheets fed through the machine and holding the same within the same positive grip throughout the printing process and until the sheets are released at a predetermined position to form an accurately aligned stack.

A feature of the present invention lies in structure which replaces feeding rollers by gripping means which assure positive feed and registration, thereby eliminating inaccurate feeding which occurs when feeding rollers wear into a frustum of a cone shape.

A still further object herein is the provision of structure capable of individual registration adjustment for each sheet handled by the machine.

Another advantage of the present machine is the provision of structure in the discharging and stacking mechanism, whereby the sheets, after having an impression put thereon, are inverted so that the printed matter thereon appears face up and a constant check up of the clarity of the printing thereon may be easily made.

Another object of the invention is the provision of an offset lithographic machine which takes up little space by virtue of the compact and cooperative arrangement of the various sub-assemblies therein.

A still further advantage of the invention is the reduction in the number and complexity of the parts whereby corresponding economies are accomplished in the manufacture and use thereof.

These objects and other ends and advantages will more fully appear in the progress of this disclosure and as pointed out in the appended claims.

In the accompanying drawings right and left hand designations indicate right and left hand sides as the operator faces the front of the ma-

chine, that is, that portion of the machine adapted to co-operate with a feeder, while the same numerals are used to indicate corresponding parts throughout the several views thereof.

5 Figure 1 is a left side elevational view of a preferred embodiment of the invention in which the feeding mechanism has been removed.

Figure 2 is an enlarged vertical sectional view of the registering and associated mechanisms as seen from the plane 2—2 on Figure 4.

10 Figure 3 is an enlarged fragmentary elevational view of a sheet carrying clip in the open position thereof as the same is about to close upon and grasp the edge of a sheet.

15 Figure 4 is a horizontal fragmentary sectional view taken along the plane 4—4 indicated on Figure 1.

Figure 5 is a view taken similarly to Figure 4 with the exception that same shows an alternate embodiment of the sheet registering mechanism.

20 Figure 6 is an enlarged fragmentary vertical sectional view taken along the plane 6—6 on Figure 5.

Figure 7 is a left side elevational view of certain of the elements shown in Figure 3 showing the cam for operating the sheet carrying clips.

25 Figure 8 is a horizontal sectional view showing in plan the alternate sheet registering mechanism which is seen in elevation in the upper right hand corner of Figure 5.

30 Figure 9 is a fragmentary perspective view showing one end of the sheet carrying clip bar.

The lithographic machine indicated generally by numeral 20 has the operating parts thereof attached or indirectly suspended from a left frame plate 21 and a right frame plate 22. The two frame plates are maintained in aligned parallel spaced position by means of known tie-bars which are transversely disposed.

35 40 A shaft 23 is suitably trunnioned in the frame plates 21 and 22 and carries fixedly mounted thereon a drum 24. Drum 24 has a circumference substantially twice the length of a sheet of paper or other material upon which the machine is adapted to operate. Drum 24 has a sheet backing portion 25 and a lithographic sheet carrying portion 26. In Figure 2 there may be seen a lithographic sheet 27, one end of

45 50 which is fixedly secured within an opening in the drum corresponding to the transversely disposed slot 28 and the other end of which is hooked by the pivotally mounted hook 29. The hook 29 serves to properly tension the lithographic sheet 27 by reason of the action of a contractile spring

30, the inner end of which is carried by a pin 31 mounted on a wall of the drum 24.

An offset or blanket drum 32 is fixedly mounted upon a shaft 33 which is trunnioned in the frame plates 21 and 22. The blanket drum 32 has mounted thereon a rubber offset blanket 34 which is secured upon the outer surface of said drum by hooking one end thereof upon a plurality of hooks 35 and by tightening said blanket by means of the hook and ratchet structure indicated by numeral 36 on Figure 2 as is well known in the art to which this invention pertains.

Shaft 23 has fixedly mounted thereon adjacent the inner surface of the left frame plate 21 a large gear 37 which meshes with a smaller gear 38 which is fixedly mounted upon the shaft 33. The ratio existing between gears 37 and 38 is two to one so that the blanket drum 32 makes two revolutions to each revolution of the drum 24, thus picking up a lithographic impression during the first revolution of drum 32 and depositing said impression upon a sheet of blank material carried by the sheet backing portion 25 on drum 24.

The individual sheets of blank material indicated generally by numeral 39 are picked up and transported through the lithographic process and subsequently discharged by structure now to be described. Two annular link chains 40 and 41 are mounted for continuous travel within the machine (see Figures 1 and 4) upon four pairs of sprockets 42, 43, 44 and 56. Sprockets 42 are mounted, one adjacent each of the frame plates upon a transverse shaft 45 which is suitably journaled in the frame plates. Sprockets 43 are mounted, one adjacent each of the frame plates upon a transverse shaft 46 which is suitably journaled in the frame plates. Sprockets 44 are mounted, one adjacent each of the frame plates upon a transverse hollow shaft 47 which rides about a shaft 48 which is suitably journaled in the frame plates. Sprockets 56 are mounted, one adjacent each of the frame plates and outwardly of drum 32 upon shaft 33. The link chains 40 and 41 have mounted therebetween two clip bars 49 and 50, the end of one of said clip bars being seen in Figure 9 of the accompany drawings. The clip bars 49 and 50 are substantially identical in construction with the exception that they are adapted for operation from opposite sides. A description, therefore, let us say, of clip bar 49 will suffice for both. The clip bar 49 has a central portion transversely disposed of the machine shown in cross section in Figure 9 indicated by numeral 51. At each end of portion 51 there are clip bar aligning segments 52 which have affixed to the upper portion thereof mounting blocks 53. Blocks 53 have threaded orifices in the top walls thereof which are engaged by screws 54. The chains 40 and 41 are each provided with two special links 55 which are equidistant from each other along the path of travel of the chains and are disposed opposite each other as said chains are mounted upon the sprockets therefor. Special links 55 have inwardly horizontally projecting tabs which are suitably orificed and are maintained in rigid connection with the blocks 53 by means of the screws 54 as best seen in Figure 5. Clip bar 49 has mounted along the portion 51 a plurality of vertically disposed adjustable pins 57. Pins 57 threadedly engage portion 51 and may be raised or lowered by inserting a screw driver in the slotted shank 58 as seen in Figure 2. The enlarged heads of pins 57 are adapted to serve as

surfaces against which grippers 59 may operate. The clip bars 49 and 50 are each provided with a plurality of grippers 59 which are fixedly attached to a transverse spindle 60 which is journaled in orifices 61 in the clip bar aligning segments 52. On clip bar 49 the spindle 60 projects to the left of the segment 52 (see Figure 5) outwardly to terminate in attachment to a cam 62. On clip bar 50 the spindle 63 projects to the right of the segment 52 which is on the right hand end of the central portion 51 and terminates in attachment to a cam 64 (see Figure 1). In order to allow the passage of spindles 60 and 63 outwardly of the sprockets which carry the chains 40 and 41, each of the sprockets in the pairs of sprockets 42, 43, 44 and 56 are provided with cut-out portions 65.

Since the clip bars 49 and 50 are affixed to the link chains 40 and 41 as has been described and these chains are carried about in a continuous travel by the four pairs of sprockets as above described, it will be understood that the clip bars 49 and 50 will be more or less free to shift during certain portions of the travel thereof by reason of the looseness in the chains themselves owing to wear in the links. In machines of the present class which are subject to continuous use at relatively high speed, considerable wear occurs in the links of the link chains 40 and 41 and this wear is not uniform throughout the length of the chains. In order to take up any undesirable slack in the chains 40 and 41, the shaft 45 is mounted so that the journailling thereof is adjustable. This adjustment may be made by any suitable means known in the art, as for example the regulation of the shaft 45 in its position within the horizontally disposed slots 66 in the frame plates 21 and 22. While slack in the chains 40 and 41 may be taken up in the manner just described, it is undesirable to have the chains running at too great a tension as this causes excessive wear and since the wear is uneven along the length of each chain, the tightening of the chains will not result in better registration of the clip bars 49 and 50 and sheets 39 carried therein with relation to the printing elements of the machine. In order to avoid such undesirable results, registering mechanism in the form of pairs of disks 67 and 68 is provided. The disks 67 are best seen in Figures 4 and 5 while the right hand one of the pair of disks 68 is seen in Figure 2. The pairs of disks 67 and 68 are provided with indentations 69 and 70 respectively which are of the same configuration as the clip bar aligning segments 52, so that when the clip bar aligning segments are placed by the chains 40 and 41 in the indentations 69 and in the indentations 70 the clip bars 49 and 50 are positively and accurately brought into register with the clip loading and lithographic printing mechanisms. The disks 67 are fixedly mounted on the hollow shaft 47 while the disks 68 are fixedly mounted on shaft 33.

The clip bars 49 and 50 are adapted to grasp and release individual sheets 39 in their travel along with the chains 40 and 41. On each of the clip bars 49 and 50 the grippers 59 are maintained in a closed or gripping position by reason of the action of coil springs 71 which encircle the spindles 60 and 63. This structure is best seen in Figure 4. The cams 62 and 64 are integrally mounted upon the outer ends of the spindles 60 and 63 which are squared at the terminals thereof so that any tendency of the cams to shift thereabout will be eliminated. The cams

62 and 64 are each provided with rollers 72 and 73 which are adapted to act as followers for cams 74 and 75. Cams 74 and 75 are mounted upon shaft 48. Shaft 48 is rotated in a clockwise direction in contrast with the hollow shaft 47 which rotates in a counterclockwise direction as viewed in Figures 2, 3 and 7. Cams 62 and 64 are adapted to coact with cams 76 and 77 respectively, cams 76 and 77 being fixedly mounted on the shaft 48 inwardly of and next to the cams 74 and 75. Since the chains 40 and 41 are moving at relatively high speed, it is necessary that the grippers 59 be opened very quickly and be closed very quickly. Shaft 48 is operated at a speed four times as fast as the shaft 23 and twice as fast as the shaft 33. This speed of operation is secured by means of a gear 78 which meshes with the gear 38 and is mounted upon a suitable stud shaft projecting inwardly from the frame plate 21, the ratio existing between gears 38 and 78 being two to one. A gear 79 meshes with gear 78 and also with a gear 80 which is fixedly mounted upon the shaft 48. The purpose of the gear 79 is merely to reverse the motion so that the shaft 48 will rotate in a direction opposite to the shaft 33. The gear 79 is mounted upon a stud shaft projecting inwardly from the frame plate 21.

Turning to Figures 3 and 7, the action of cam 62 and the roller thereon, and cams 74 and 76 will now be described. In Figure 3, when the machine is in operation the chain 40 is moving as it passes about the sprocket 56 in a counterclockwise direction. The projection 81 of the cam 76 strikes the projection 82 of the cam 62 as seen in the lower corner of Figure 7. Since the projection 81 is travelling downwardly as seen in that view, the cam 62 is rotated in a counterclockwise direction together with the spindle 60 and the gripper 59 is swung back to its open position. The projection 83 on cam 62 engages the indentation 84 in the cam 76. The projection 85 on the cam 76 engages the surface 86 on the cam 62 which serves to maintain the cam 62 rotated about in a counterclockwise manner and the grippers 59 in their open position. The projection 83 rides upon the dwell surface 78 of cam 76 and the projection 83 then rides upon the fall surface 88 of the cam 76 until the cam 62 rotates so that the roller 72 strikes the dwell portion 89 of cam 74. Further rotation of the shaft 48 with concurrent opposite movement of the chain 40 will result in a position shown in Figure 3 in which the gripper 59 is just about to snap closed over a sheet 39. The closing of the gripper 59 is accomplished in an extremely rapid manner by reason of the sudden fall portion 89 of the cam 74 allowing the roller 72 to swing downwardly as viewed in Figure 3 to the normal closed position of the grippers 59 and a position in which the roller 72 and the cam 62 are entirely free of mechanism contacting same.

A sheet 39 of paper or other material is held upon a clip bar either 49 or 50 between the grippers 59 and the enlarged heads 91 of the pins 87, and is carried along by the movement of the clip bar as the same moves with the chains 40 and 41 so that said sheet 39 passes between the sheet backing portion of the drum 24 and the offset blanket 34 on the blanket drum 32 and receives a lithographic impression therefrom. The sheet 39 is then carried to the rear of the machine or to the left as viewed in Figure 1, and is supported and prevented from falling between

the chains 40 and 41, since only the forward edge thereof is gripped by the clip bar, by a plurality of spaced skids 92 (see Figure 1) which are curved at the lower ends thereof as indicated by numeral 93. Skids 92 are maintained in position by clamps 94 which secure same to a transverse tie-bar 95 extending between the frame plates 21 and 22. As a clip bar carrying a sheet as previously described changes its direction of travel, in passing about the sprockets 42 the sheet 39 is inverted and pulled forwardly in the machine in a horizontal direction. Said clip bar in moving forwardly of the machine is adapted to have either the roller 72 or the roller 73 strike stationary cam bars 96 or 97 respectively which open the grippers 59 sufficiently to release and allow same to fall upon an angularly disposed table 98 having side guides 99 and an end guide 100. Table 98 is suitably supported at the lower end thereof upon a tie-bar 101 and at the upper end thereof upon a tie-bar 102. The chains 40 and 41 are supported against any undesirable sagging by means of horizontally disposed guides 103 and 104 which are suitably attached to the frame plates 21 and 22 by suitable brackets extending inwardly therefrom, as for example the bracket 105 as seen in the lower right hand corner of Figure 4. The stationary cam bars 96 and 97 are supported from the guides 103 and 104 respectively by means of brackets 106. A clip bar having been unloaded in the manner just described, that is, by coacting with the stationary cam bar therefor, changes its horizontal direction of travel about the sprockets 43 and travels upwardly to be acted upon by the clip loading mechanism as has been described above.

Turning now to the first embodiment of the clip bar loading mechanism illustrated in Figures 2, 3, 4 and 5, the structure utilized for securing accurate registration of the sheets 39 within the clip bars 49 and 50 will be described. Supported by a tie-bar 107 are a pair of brackets 108 which carry affixed to the upper surface thereof a curved paper feeding table 109. The table 109 is situated at a level to co-operate with a paper feeding device of any suitable type adapted to feed sheets of paper singly thereon from a stack. The rear edge of the paper feeding table 109 is provided with a plurality of indentations 110 through which the open grippers 59 may pass upwardly and rearwardly (see Figure 4). Placed between the indentations 110 are a plurality of smaller indentations 111 within which are disposed, in the lowered position thereof, a plurality of stops 112. For purposes of clarity and since they are all identical with each other, only one of the stops 112 is shown in the drawings. Stop 112 includes a body portion 113 in the form of a collar, a rearwardly extending integral bifurcated portion 114, a spring 115 attached to the rear ends of portion 114, and a pivotally mounted finger 116. The finger 116 is pivotally mounted at the upper end thereof on a short pin 117 which is trunnioned within the bifurcated portion 114. As best seen in Figure 2, finger 116 may be rotatably adjusted within narrow limits by a set screw 118 and lock nut therefor which is threadedly mounted in a downwardly extending projection 119 integrally extending from body portion 113. Body portion 113 is mounted upon a transverse shaft 120 and secured thereto by a set screw 121 which is journaled in the frame plates 21 and 22 and is provided at the right end thereof with a short crank arm 122 having a horizontally projecting pin 123 which engages a

notch 124 in a reciprocable sliding bar 125. Bar 125 at the rear end thereof is provided with a roller 126 adapted to coact with a plate cam 127 which is fixedly mounted upon the shaft 23. Bar 125 is mounted for substantially horizontal oscillation by means of a hollow guiding block 128 which is affixed to the inner surface of the frame plate 22. The inner surface of guide block 128 is provided with a pin 129 which serves as a stationary mounting for the rear end of a coil spring 130, the forward end of which is connected to a pin 131 affixed to the bar 125. Since the pin 131 acts also as a stop in striking against the forward end of the block 128, the roller 126 is enabled to coact with only the upper portion of the cam 127 which includes a low dwell 132, a rise 133 and a high dwell 134.

By the structure just described, the finger 116 takes three positions during a cycle, that is, during a complete revolution of the drum 24, or during the feeding and printing of one sheet 39. The first position is an inactive position when the pin 131 contacts the block 128. The second or registering position is when the roller 126 is riding upon the low dwell 132. In this position the finger 116 is moved rearwardly by the action of the cam 127 a predetermined amount, yet the exact and final positioning of the finger 116 may be secured by manipulation of the set screw 118. The set screw 121 is used mainly for transverse adjustment of the finger 116. As soon as the grippers 59 have closed upon the sheet 39 and have securely clamped the same upon the clip bar, the finger 116 is rapidly arcuately retracted to the rear of the machine by the rise 133, so that the finger 116 does not interfere in any way with the subsequent feeding of the sheet 39 and the movement of the clip bars. The finger 116 is held in the retracted position by the high dwell 134 until it is necessary that the finger 116 be lowered to perform another registering operation. In the embodiment just described, it will be noticed that inasmuch as there are two clip bars 49 and 50 being transported by the chains 40 and 41 and there is only one cam 127, there is only one registering position which is applied to each of the clip bars.

In a printing machine of the type herein described adapted to operate at high speed, it is imperative that accurate registration occur at all times, and while the mechanism just described hereinabove is suitable for some classes of work, as for example where the registration need only be relatively exact with relation to the paper edge, a requirement in the case of single color printing, where it is desired to place more than one impression on the same sheet in exact registration as in color work, it is necessary that each sheet be individually registered within its respective clip bar as the clip bars are loaded. The second embodiment of the clip bar registering structure accomplishes that purpose and is illustrated in Figures 5, 6 and 8.

Since each of the clip bars 49 and 50 are closed by the action of springs 71, it is practically impossible to get the tension of the springs on each of the clips to exactly the same value and as the machine operates at a rapid speed, the speed of the closing of the grippers 59 is affected by the tension value of the springs 71 after the cams 74 and 75 release the rollers 72 and 73. The structure described with regard to the stops 112 and their mounting upon the shaft 120 is the same in the case of the second embodiment as in the first, so that in the second embodiment the

cam 127 and the bar 125 are supplanted by different structure. The shaft 23 (see Figure 6) is provided with a pinion 135 fixedly mounted thereon which meshes with a gear 136 fixedly mounted upon a short shaft 137 which is journalled at the inner end thereof in a bracket 138 affixed to the frame plate 22 by means of the bolts 139, while the outer end thereof is journalled in the frame plate 22. The action of the pinion 135 and the gear 136 is to reduce the speed of the shaft 137 so that the same revolves at a speed one-half of the speed of revolution of shaft 23. Mounted upon the shaft 137 are a pair of cams 140 and 141. Cams 140 and 141 have low dwell portions 142 and 143, rise portions 144 and 145, and high dwell portions 146 and 147, respectively. A pair of reciprocable sliding bars 148 and 149 are adapted to coact with cams 140 and 141 respectively, and have attached to the rear ends thereof rollers 150 and 151, downwardly extending lugs 152 and 153, pins 154 and 155 adjacent the forward ends thereof, and vertically upwardly projecting pins 156 and 157 respectively. The pins 156 and 157 are resiliently connected to the frame plate 22 by means of coil springs 158 and 159 which have the forward ends thereof attached to the pins 156 and 157 and have the rear ends thereof attached to the pins 160 and 161 which project horizontally inwardly from the frame plate 22. The action of the springs 158 and 159 is to urge the bars 148 and 149 rearwardly so that the rollers 150 and 151 coact with the cams 140 and 141. The bars 148 and 149 are adapted for horizontal reciprocation by being mounted within a pair of guide blocks 162 and 163 which are affixed to the inner surface of the frame plate 22. The shaft 120 is provided with a pair of collars 164 and 165 having short radial arms 166 and 167 integral therewith, each of which is provided with an adjustable set screw 168 and 169 and lock nut therefor which are adapted to coact with the lugs 152 and 153. The low dwell portions 142 and 143 are adapted to allow the bars 148 and 149 to move rearwardly together with the lugs 152 and 153 respectively, which allows two independently adjustable positions for the shaft 120 at the time when a sheet 39 is registered or located for each of the clip bars 49 and 50, while the high dwell portions 146 and 147 move the bars 148 and 149 forwardly, thereby moving the stops 112 out of the way of the sheets 39 as advanced by the clip bars 49 and 50. The pins 154 and 155 serve as stops to prevent the springs 158 and 159 from moving the bars 148 and 149 too far rearwardly when the cams 140 and 141 are in positions whereby the rollers 150 and 151 are not acted upon by said cams. It may now be seen that absolute registration may be obtained by the present invention for each individual sheet as the same is placed in position to be gripped by the clip bars and printed, making the present invention especially adapted for high speed multi-color lithographic printing.

The relation of the various parts may be manually adjusted by means of a hand wheel 170 (see Figure 1) which is mounted upon a shaft 171 journalled between frame plates 21 and 22 which carries thereon a gear adapted to mesh with the gear 37. Power is supplied to the printing machine in any suitable manner, as for example by the sprocket chains 172 and 173 and sprockets not specifically shown on the shaft 102 and a motor 174 as is well understood by those versed

in the art to which the present invention relates.

I have disclosed an offset lithographic printing machine being adapted for continuous feed at high speed and in which absolute registration is provided at two important points in the operation cycle, one at the inception of the gripping or grasping by the link chain carrier of each individual sheet, and another at the initiation of the printing operation, that is, when the sheet is compressed between the large drum carrying the lithographic sheet and the first sheet supporting portion in the small drum having the offset rubber blanket thereon. As is well known in the art, once the printing operation is begun and the sheet is tightly compressed between the two drums, further means for securing registration are not necessary inasmuch as no shift is allowed owing to the pressure between the two drums. The accurate registration of the sheets at the two important points just described is secured by means of the clip bar aligning segments 52 which nest accurately within the indentations 69 in the disks 67 and in the indentations 70 in the disks 68. The individual sheets after being printed are drawn rearwardly in the machine and inverted and released to form a stack with the printing thereon face uppermost so that the accuracy and quality of the printing may be checked up while the machine is in operation.

The foregoing description has been made rather detailed for clearness and understanding only, and no unnecessary limitations should be understood therefrom, but the appended claims should be construed as broadly as permissible in view of the prior art.

I claim:

1. A printing machine comprising rotary printing means including a cylinder adapted to progressively place a printed impression on a moving sheet along a certain printing line parallel to the axis of said cylinder, said line being stationary with relation to the periphery of said cylinder and said moving sheet; a continuous moving conveyer approaching said printing line along a first rectilinear path of travel substantially tangential at the printing line to said cylinder and leaving said line along a second rectilinear path of travel substantially tangential at said printing line to said cylinder; sheet gripping means on the conveyer adapted to grasp the leading edge of said sheet; registering means, associated with said cylinder, adapted to engage the gripping means for aligning same in predetermined relation with said cylinder at the inception of the printing operation on said sheet, said registering means and said gripping means becoming disengaged immediately thereafter by reason of the second tangential path of travel of the conveyer.

2. A printing machine comprising rotary print-

ing means including a printing cylinder and a paper supporting cylinder, said cylinders being parallel mounted and adapted to compress a moving sheet between them whereby the printing cylinder may progressively place a printed impression on said sheet along a certain stationary printing line disposed parallel to the axes of said cylinders at the point of their greatest proximity; a continuous moving conveyer approaching said printing line along a first rectilinear path of travel substantially tangential to said cylinders at the printing line, and leaving said line along a second rectilinear path of travel substantially tangent to said cylinders at the printing line; sheet gripping means on the conveyer adapted to engage the leading edge of said sheet; registering means associated with the printing cylinder adapted to engage the gripping means for aligning same in predetermined relation with the printing cylinder at the inception of the placing of a printed impression on said sheet, said registering means and said gripping means becoming disengaged immediately thereafter because of the second tangential path of travel of the conveyer.

3. A printing machine comprising rotary printing means; a continuous conveyer; sheet gripping means on the conveyer; a rotating disc having a V-shaped indentation in the periphery thereof, said disc being disposed adjacent the rotary printing means; the peripheral speeds of the printing means and the disc being in synchronism with the speed of travel of the movable conveyer; a corresponding V-shaped block portion of said gripping means being adapted for engagement within the indentation on the disc at the inception of the printing operation whereby a sheet on said gripping means is brought into a predetermined registration with relation to the rotary printing means.

4. A printing machine comprising rotary printing means; a feeding table; a continuous conveyer; sheet gripping means on the conveyer; a rotating disc independent and spaced from said rotary printing means, having an indentation in the periphery thereof, said disc being disposed adjacent the feeding table; actuating means moving in a direction opposite to the path of travel of the conveyer for operating the sheet gripping means; the peripheral speeds of the printing means and the disc being in synchronism with the speed of travel of the movable conveyer and with the actuating means; a portion of said gripping means being adapted for engagement within the indentation on the disc while a sheet is being loaded into the gripping means and while the said actuating means is functioning whereby said sheet is gripped within the gripping means in a predetermined position or registration with relation to said gripping means.

ROY ABERLE.
